JAR

William H. Buckley, New York, N.Y., assignor to Standard Brands Incorporated, New York, N.Y., a corporation of Delaware

Filed July 31, 1961, Ser. No. 66,142

Term of patent 14 years

(Cl. D58—25)

FIG. 2

FIG. 1 is a side elevational view of the jar embodying my new design, the jar having the same appearance from all sides; and

FIG. 2 is a bottom view of the jar shown in FIG. 1, dotted lines being employed to indicate that the successive upwardly extending ribs are continued entirely around the jar.

The dominant features of my design reside in the portions shown in full lines.

I claim:

The ornamental design for a jar, as shown and described.
